TELEVISION SYSTEM AND THE METHOD OF
OPERATION THEREOFAlda V. Bedford, Collingswood, N. J., assignor to
Radio Corporation of America, a corporation of
DelawareApplication May 29, 1934, Serial No. 728,147
Renewed June 17, 1938

49 Claims. (Cl. 178—7.2)

My invention relates to improvements in television systems and the method of operation thereof.

In television systems embodying a cathode ray tube at both the transmitting and receiving stations, it has been found to be advantageous to cause the cathode rays to scan the respective screens in such manner that the horizontal lines of alternate frames fall in the spaces between the horizontal lines of the intervening frames. For example, the horizontal lines of the odd frames are spaced a distance about equal to the width of a line, and the horizontal lines of the even frames, which are similarly spaced, fall between the lines of the odd frames. On account of the persistency of vision, the optical effect is the same as though each frame comprised twice the number of lines. A system of this type is disclosed in the copending application of Randall C. Ballard, Serial No. 623,325, filed July 19, 1932. This distinctive action of scanning is sometimes referred to as "interlaced" scanning. For the purpose of obtaining the so-called interlaced pattern, the cathode ray is deflected horizontally an odd number of times every two frames, the relation of the line frequency to the frame frequency being such that the scanning of each odd frame starts at the same point at the upper left hand corner of the screen, while the scanning action for each even frame starts at the same point which is a distance of one-half a line to the right from the common starting point for the odd frames. In this way, the lines of the even frames are disposed in the spaces between the lines of the odd frames.

For the purpose of synchronization and framing in the systems referred to, a synchronizing signal is transmitted at the end of each scanning line and utilized at the receiver to drive the circuit for deflecting the cathode ray horizontally. At the end of each frame a framing signal is transmitted and utilized at the receiver to drive the circuit for deflecting the ray vertically. On account of the relation referred to, the odd and even framing signals occur at different times with respect to the synchronizing signals. The effect of this, at the receiver where a filter is used to separate the synchronizing signals from the framing signals, is to cause the odd framing signals to have a slightly different shape than the even framing signals in the output connections from the filter. The precise timing required to obtain the uniform spacing of the interlaced lines is therefore lost unless the various adjustments and operating conditions are exactly right.

In the systems referred to, furthermore, occurrence of the framing signals prevents any synchronizing signals from being effective during the periods of occurrence of the framing signals. During these periods, therefore, a relatively slight electrical disturbance or misadjustment is effective to cause the scanning action at the receiver to fall out of time with that at the transmitter.

In the systems referred to, furthermore, undesirable electrical effects are developed due to return deflection of the cathode ray at the transmitter, the action of cutting off the ray during the return line periods, and, in the transmission of moving picture film, the action of flashing images of the pictures onto the photosensitive surface of the usual screen.

In the various television systems proposed heretofore, furthermore, the direct current component of the signals is lost during the operating action at the transmitter. The effect of this is manifested at the receiver by production of an image whose overall brilliancy or background does not necessarily correspond with that of the object being transmitted.

With the foregoing in mind, it is one of the objects of my invention to provide an improved television system and method of operation whereby the odd and even framing signals referred to above are, for all practical purposes, identical at the points or connections wherat they are used to control the vertical deflecting circuit, so that deflection of the cathode rays is more readily and accurately controlled than has been possible by the various systems and methods proposed heretofore.

Another object of my invention is to provide an improved television system and method of operation in which the undesirable electrical signals or other disturbing electrical effects referred to are either eliminated or compensated for at the transmitter without interfering with the development and transmission of the desired picture, synchronizing and framing signals.

Another object of my invention is to provide an improved television system and method of operation whereby there is developed a signal wave which forms part of and is transmitted with the entire signal wave. This signal wave is representative of the required direct current component which can be utilized at the receiver to vary the background of the reproduced picture automatically and in accordance with occurring variations of the overall brilliancy or background of the object at the transmitter.

Other objects and advantages will hereinafter appear.

In accordance with my invention, additional or auxiliary electrical signals, similar in size and shape to the synchronizing signals, are transmitted with the latter during periods embracing the periods of occurrence of the framing signals. In the specific embodiment of my invention, synchronizing signals are developed and transmitted at a frequency twice the line frequency during periods slightly greater than and embracing the periods of occurrence of the framing signals.

Further, in accordance with my invention, the framing signals are interrupted, and synchronizing signals are caused to occur during the interruption periods whereby the circuit for horizontal deflection of the ray is supplied with synchronizing signals during the framing periods. The action is such that interruption of the framing signals does not interfere with their effectiveness in controlling the circuit for vertical deflection of the cathode ray.

Further, in accordance with my invention, the picture signals developed at the transmitter are supplied to an amplifier comprising a plurality of tubes, some of which are driven to saturation during the periods of return deflection of the ray so that the undesirable electrical signals developed during these periods do not appear in the output wave from the amplifier. At a later stage in the amplifier, the synchronizing and framing signals are supplied and transmitted with the picture signals.

My invention resides in the improved system and method of operation of the character hereinafter described and claimed.

For the purpose of illustrating my invention, an embodiment thereof is shown in the drawings, wherein

Figure 1 is a diagrammatic view of a television transmitting system constructed and operating in accordance with my invention;

Fig. 2 is an enlarged, detail, sectional view, the section being taken on the line 2-2 in Fig. 1;

Fig. 3 is an enlarged elevational view of the disc in Fig. 1 for developing the synchronizing and framing signals;

Fig. 4 is an enlarged fragmentary view, taken from Fig. 3;

Figs. 5 to 20 are graphical views, illustrative of the principle of operation in Fig. 1;

Fig. 21 is a diagrammatic view of one form of television receiving apparatus for intercepting and utilizing the signals transmitted by the system in Fig. 1 to produce an image of the object; and

Fig. 22 is a detail diagrammatic view of one of the circuits in Fig. 1.

With reference to Fig. 1, the picture signals are developed by a cathode ray tube 10 provided with a screen 12. This screen is of the usual construction and comprises a sheet of insulation material provided on the surface 14 thereof with a large number of minute, metallic, photosensitized elements, spaced and insulated from each other. The insulating sheet is provided over the opposite surface thereof with a sheet or coating of electrically conductive material to which an output connection 16 is made.

The tube 10 is provided with an electron gun 18 for developing a ray 20 of electrons and directing the same at the mosaic photosensitive surface 14 of the screen. The gun comprises a cathode 22, a grid 24 for controlling the intensity of the ray, and an anode 26 for accelerating the

electrons. A second anode 28, which may be in the form of a silver coating on the inside surface of the tube, is maintained at a relatively high potential positive with respect to the potential on the first anode 26, and operates in cooperation with the latter to focus the ray of electrons to a relatively small spot on the screen 12. The various electrodes of the tube are supplied as usual with suitable operating potentials, as represented in the drawings.

For the purpose of causing the ray 20 to scan the screen 12, a circuit 30, connected as shown to the coils 32, develops a voltage wave of the required shape and frequency to cause a saw-tooth current wave to pass through these coils at a frequency of 7290 cycles, and a circuit 34, connected as shown to the coils 36, develops a voltage wave of the required shape and frequency to cause a saw-tooth current wave to pass through the coils 36 at a frequency of 60 cycles. Under these conditions, during every odd frame the ray 20 is made to scan the screen along the same horizontal lines spaced from each other a distance about equal to the width of a line, and during every even frame to scan the screen along the same horizontal lines which always fall in the spaces between the lines of the odd frames.

The object is represented as being a moving picture film 38, and the apparatus for projecting the individual pictures onto the screen surface 14 is shown as being the same as that described in detail in my copending application, Serial No. 653,947, filed January 28, 1933. This apparatus comprises a disc 40 provided with diametrically opposite openings 42 and 44 and driven at a constant rate of 30 revolutions a second by a synchronous motor 46. The film 38 is fed intermittently through a gate 48 at the rate of 24 pictures a second by means of suitable intermittent mechanism 50 driven from the motor shaft. This intermittent mechanism is described in my copending application referred to. By means of a light source 52 and the lens system shown, an image of the individual film pictures is flashed onto the photosensitive screen surface 14 when each of the openings 42 and 44 passes across the field of view.

The relation and timing of the mechanical and electrical parts with respect to each other is such that the film is stationary in the gate 48 during the periods that the openings 42 and 44 expose the screen 12 to the light, and these periods are equal to and occur simultaneously with the periods during which return deflection of the ray 20 takes place in the vertical direction. During the periods that the disc 40 cuts off the light to the screen 12, the ray 20 scans the screen once.

The action of the intermittent mechanism 50 is such that each of the odd pictures, for example, is left stationary in the film gate 48 for 60 projection three times onto the screen 12, while each of the even pictures is held stationary in the film gate for projection twice onto the screen. Since 12 odd pictures and 12 even pictures are fed through the gate 48 every second, there will be 60 periods every second during which an image of a film picture is flashed onto the screen 12. Due to this action, it is possible to feed the film at the rate of 24 frames a second and to scan the screen 12 at the rate of 60 times a second.

The means for developing the synchronizing and framing signals comprises a disc 54 which is rotated at the rate of 30 revolutions per second by a synchronous motor 56 supplied from the same source 58 as the motor 46.

Light from a source 60 is focused on this disc, and passes through openings therein disposed and shaped as shown in Figs. 3 and 4. A photoelectric cell 62 exposed to the light coming through these openings develops the synchronizing and framing signals. These signals are amplified by an amplifier 64 and supplied to a filter 65 which separates the two kinds of signals. The synchronizing signals are taken from the filter by a connection 66 and supplied to the horizontal deflection circuit 30. A connection 68 from the filter supplies the framing signals to the vertical deflection circuit 34.

For the purpose of causing the maximum 15 of light to reach the photoelectric cell 62, the lens 70 is used to focus the light from a source 60 on a slit 72 in a mask 74, and a second lens 76 is used to focus the light from the slit 72 on the openings in the disc 54, as more clearly shown 20 in Fig. 2. The openings in the disc 54 through which light from the source 60 shines are in the form of slits 78, 243 in number, evenly spaced, and disposed at the outer edge of the disc. The slit 72 is about the same size and 25 shape as the slits 78.

The disc 54 is also provided with two openings 80 and 82 diametrically opposite to each other, and through which the light shines to develop the framing signals. As shown in Fig. 4, the 30 framing opening 80 is interrupted to make room for a synchronizing slit 78, and the framing opening 82 is likewise interrupted to make room for a synchronizing slit 78. The areas of the 35 sectional openings comprising the openings 80 and 82 are such that the total open area in each case is equal, so that the same amount of light will pass through each of these openings. Additional slits 84, similar to and spaced the same as the slits 78, are disposed as shown about the 40 framing opening 80 and between the slits 78. One of the slits 84 is disposed in the remaining gap in the framing opening, as shown. Likewise, additional slits 86, also similar to and spaced the same as the slits 78, are disposed about the 45 framing opening 82. One of the slits 86 is disposed, as shown, in the remaining gap in the openings 82. With the disc 54 rotating at the rate of 30 revolutions a second, synchronizing signals will be developed at the rate of 7290 a second, and framing signals will be developed at the rate of 60 a second. These signals are applied 50 to a connection 88 and through a resistance 90 to the output connection 92 from an amplifier comprising the tubes 94, 96, 98, 100 and 55 102.

The disc 54 is also provided with a second set of slits 104 evenly spaced about the edge of the disc by an amount to make room for 243 of these openings. Elongated openings 106 and 108 are 60 disposed diametrically opposite and on the same circumference as the slits 104. Each of the openings 106 and 108 extends over a distance equal to about seven times the distance between two adjacent slits 104. The effect of this is to develop 65 a relatively strong signal of substantially constant amplitude and which occurs during the period of each return deflection of the ray 20 in the vertical direction. Light from a source 110 shines through the slits 104 and the openings 70 106 and 108 to a photoelectric cell 112 to develop electrical signals which are amplified by an amplifier 114. The disposition of the slits 104 is such that a signal is developed at the end of each scanning-line period. The purpose of these signals will hereinafter more fully appear. Light

from the source 110 is focused on the slits and openings in the same manner shown in Fig. 2.

The amplified signals from the amplifier 114 are applied by way of a condenser 116 and a connection 118 to the control grid 24 of the electron gun, and are taken from a stage of this amplifier whereat they are of negative polarity and of sufficient amplitude to cut the ray 20 off during each of the periods of return deflection of the ray in both the horizontal and vertical directions. The signals from the amplifier 114, at positive polarity, are also applied by way of a resistance 120 and a connection 122 to the grid circuit of the tube 96.

The disc 54 is also provided with openings 124 15 and 126 disposed diametrically opposite to each other and concentrically about the axis of rotation. The length of each of these openings is about twelve times the distance between two adjacent slits 104. Light from a source 128 is 20 focused on the openings 124 and 126 in the same manner shown in Fig. 2, and excites a photoelectric cell 130 to develop relatively strong signals each of a duration equal to twelve times 25 a scanning-line period. These signals are amplified by an amplifier 132 and, at positive polarity, are applied by way of a resistance 134 and connections 136 and 122 to the grid circuit of the tube 96.

The picture signals developed by the tube 10 30 30 are amplified by an amplifier 137 and applied by a connection 138 to the grid circuit of the tube 94.

With 243 synchronizing signals occurring for every two framing signals, for the purpose of obtaining the so-called interlaced scanning action, 35 as explained, the framing signal for every odd frame, represented at 80x in Fig. 5, and the framing signal for every even frame, represented at 82x in Fig. 6, would occur at different times with respect to the synchronizing signals represented at 78x. The effect of this, in the systems proposed heretofore, is illustrated in Fig. 7. The full line curve 135 represents what the output wave in the line 68 from the filter 65 would be for the even frames, and the broken line curve 45 137 represents what the output wave in the line 68 would be for the odd frames. Due to the retention in the filter 65 of the charges produced by the synchronizing signals in the input wave to the filter, the curves 135 and 137 will differ 50 in size and shape, as represented. The framing signal for each odd frame, represented at 80y, and the framing signal for each even frame, represented at 82y, will therefore be different in size and shape. For this reason, the timing for 55 vertical deflection of the cathode ray tends to be inaccurate, in which case the odd and even lines will not have the required spacing and positions with respect to each other to obtain a properly 60 interlaced pattern.

As explained, another disadvantage of the conditions as represented in Figs. 5, 6 and 7 resides in the fact that occurrence of each framing signal prevents any simultaneously occurring synchronizing signal from being effective to drive 65 or control the circuit for horizontal deflection of the ray.

The nature of the output electrical wave from the filter 65 in my improved system is illustrated by Figs. 8, 9 and 10. On account of the sectional formation of the framing openings 80 and 82 in the disc 54, there will be interruptions in the framing signal for the odd frames, represented at 80a, and the framing signal for the even frames, represented at 80b. During one of these inter- 75

ruption periods there will occur an effective synchronizing signal represented at 78a. Likewise, there will occur an effective synchronizing signal 78b during one of the periods of interruption of the framing signal for the even frame, represented at 80b.

Due to the additional slits 84 in Fig. 4, there will occur auxiliary signals as represented in Fig. 8 at 84a, and these signals will be similar to the synchronizing signals and will occur at the same times as the synchronizing signals would occur if the frequency of the latter were doubled during a period of time slightly greater than and embracing the period of occurrence of the framing signal represented at 80a. As represented in Fig. 8, one of the auxiliary signals occurs during a period of interruption of the framing signal represented at 80a. In like manner, due to the additional slits 86 in Fig. 4 there will occur auxiliary signals represented at 86a in Fig. 9, similar in size and shape to the synchronizing signals. One of these auxiliary signals occurs during a period of interruption of the framing signal for the even frames, as shown. These auxiliary signals will occur at the same times as the synchronizing signals would occur if the frequency of the latter were doubled during a period of time slightly greater than and embracing the period of occurrence of the framing signal for the even frames, represented at 80b.

The synchronizing and framing signals or impulses shown in Figs. 8 and 9 may be described from a somewhat different viewpoint. To assist in the description, the several portions of the framing signal 80a which are separated by the interruptions are indicated as 80a₁, 80a₂ and 80a₃ while the several portions of the framing signal 80b are indicated as 80b₁, 80b₂ and 80b₃.

The space between the signal portions 80a₁ and 84a may be referred to as a slot. The space between portions 80a₂ and 78a is another slot. Likewise, the space between 80b₁ and 78b and the space between 80b₂ and 86a may be referred to as slots in the framing signal.

Thus, the back or trailing edge of the slot between 80a₁ and 84a occurs in the same time relation as the front or leading edges of the horizontal synchronizing signals. The same is true of the slot between 80a₂ and 78a with respect to the auxiliary signals. The same thing, of course, is true of the slots in the framing signal 80b.

It will be noted that the back edges of the above-mentioned slots in the framing signals increase in amplitude in the same direction with respect to time, as do the front or leading edges of the horizontal synchronizing signals and the auxiliary signals. Therefore, these back edges produce the same kind of signal in the horizontal separating or differentiating circuit shown in Fig. 21 as do the front edges of the horizontal synchronizing signals.

The signal shown in Fig. 8 may also be described accurately by saying that the framing signal portions 80a₁, 80a₂ and 80a₃ follow, or occur immediately after, the synchronizing signals 78x, 84a and 78a, respectively.

With conditions as represented in Figs. 8 and 9, there is greater symmetry of the synchronizing signals with respect to the framing signals for the even and odd frames. The result is that the output wave from the filter 65 for the odd frames will be as represented in Fig. 10 by the curve 80z, and the output curve from this amplifier for the even frames will be as represented by the broken-

line curve 82z. With the electrical waves for both the odd and even frames practically identical during the periods of occurrence of the framing signals, the latter will be the same in size and shape for both the odd and even frames. For this reason the timing for vertical deflection of the ray will be accurate, so that the respective points at which the ray starts to scan the odd and even frames will be definitely fixed to maintain the desired action for interlaced scanning, even though there might occur a relatively slight electrical disturbance or misadjustment. While the additional or auxiliary signals represented at 84a and 86a are similar to the synchronizing signals, they are not effective to change the frequency of operation of the horizontal deflecting circuit 30 for the reason that this circuit has considerable "inertia" which makes it insensitive to any signals except those which are occurring in time with its natural period of oscillation.

The action just described, whereby the odd and even framing signals are made substantially the same in size and shape, might be improved further by making some of the slits 84 and 86 slightly wider or narrower than the others, or by making one or more of these slits wider and one or more of these slits narrower than the others. The effect of this is to cause the duration of one or more of the auxiliary signals to be less than that of the others, as represented by dash lines in Fig. 8, or the duration of one or more of the auxiliary signals to be greater than that of the others, as represented by dash lines in Fig. 9. Another modification of wave shape which would produce substantially the same result is one in which the additional impulses 84a and 86a are omitted and the vertical synchronizing impulses 80a and 80b are made slightly different from one another in shape or duration in order to compensate the dissymmetry of timing of the horizontal synchronizing impulses 78x with respect to the vertical synchronizing impulses.

The synchronizing signals which occur during the periods of interruption of the framing signals are effective to drive the horizontal deflection circuit 30. This circuit is therefore positively driven at all times, so that it does not drift out of synchronization during the interval of the framing signal.

It has been determined that although the framing signals are interrupted for the purpose explained, they are still effective to drive or control the vertical deflection circuit 34 satisfactorily.

The filter 65 permits substantially only the synchronizing signals to pass to the horizontal deflection circuit 30 by way of the connection 66, and only substantially the framing signals, which have a substantially different steepness of wave front than the synchronizing signals, to pass to the vertical deflection circuit 34 by way of the connection 68.

When an image of a picture of the film 38 is flashed onto the mosaic photosensitive surface 14 of the screen 12, electrostatic charges are stored at the individual elements referred to, the value of the charge stored at any particular elemental area of the screen corresponding to the value of light intensity to which this elemental area has been exposed. As the ray 20 is deflected horizontally across the screen from left to right, as viewed looking toward the right in Fig. 1, picture signals represented at 142 in Fig. 11 are developed during the time T in the output connection 138.

from the amplifier 137. At the end of this time, a synchronizing signal occurs and is effective with respect to the horizontal deflection circuit 30 to cause return deflection of the ray during the time t . During the time t , one of the signals from the amplifier 114, represented at 144 in Fig. 13, is applied at negative polarity to the grid 24 to cut off the ray 20. One of these signals occurs during each of the return periods t . The action 10 of cutting off the ray 20 and deflecting it back across the screen causes development, during the periods t , of undesirable signals represented at 146 in Fig. 11.

At the end of each frame a framing signal 15 occurs and is effective with respect to the vertical deflection circuit 34 to cause return deflection of the ray in the vertical direction, this action taking place during a period equal to $4(T+t)$. At this time a signal, represented at 148 in Fig. 20 13, and which is caused by one of the openings 106 and 108 in Fig. 3, occurs, and is applied at negative polarity to the grid 24 to cut off the ray. The action of cutting off the ray at this time 25 and causing it to return vertically produces an undesirable signal.

The action of flashing the pictures onto the screen 12 in the manner explained occupies a period equal to $12(T+t)$, and causes development in the output connection 138 of an undesirable 20 signal represented at 150 in Fig. 11. During this same period, one of the openings 124 and 126 is effective to cause development in the connection 136 of an electrical signal represented at 152 in Fig. 14, and which is of positive polarity.

With the arrangement and connections as described and shown in Fig. 1, the electrical wave in the output connection 138 from picture-signal amplifier 137 will be as represented in Fig. 11, with the picture signals representative of conditions of light at the object, of positive polarity. This wave is applied to the grid circuit of the tube 94, as shown. In the output circuit of the tube 94 this wave will be the same shape as that in the grid circuit, but will be reversed in polarity, 45 as represented in Fig. 12.

The wave from the output of the amplifier 114, and in the resistance 120, will be as represented in Fig. 13, with the signals of positive polarity. The wave from the output of the amplifier 132, 50 and in the connection 136, will be as represented in Fig. 14, with each signal of positive polarity.

The waves as represented in Figs. 13 and 14 are applied by the connection 122 to the grid circuit of the tube 96 and combine with the wave 55 of Fig. 12 to produce an input wave to the tube 96 as represented in Fig. 15. This wave is reversed in polarity by the tube 96, and appears in the plate circuit thereof as represented in Fig. 16. The wave as represented in Fig. 16 is applied to the input circuit of the tube 98 which is 60 so biased that any signals, more negative than those at the level represented at 160 in Fig. 16, are effective to drive this tube to cut off. In this way practically all the undesirable signals which 65 were developed during the periods of horizontal and vertical return deflection of the ray are eliminated. The output wave from the tube 98 will therefore be as represented in Fig. 17, and will be reversed in polarity by the tube 100 and 70 appear in the output circuit of the latter and in the grid circuit of the tube 102 as represented in Fig. 18. The tube 102, similar to the tube 98, is so biased that any signals, more negative than those at the level represented at 162 in Fig. 18, 75 are effective to drive this tube to cut off. In this

way, any of the undesirable signals referred to which are not removed by the tube 98 are eliminated by the tube 102. The output wave from the tube 102 will therefore be as represented in Fig. 19. This wave is comprised of the picture signals represented at 142, the signals represented at 144 and which have a duration approximately equal to t , and the signal represented at 152 and which has a duration equal to $12(T+t)$. The wave in the connection 88 from the output of the amplifier 64 is as represented in Figs. 8 and 9, and is applied as shown to the output circuit of the tube 102 and combine with the wave of Fig. 19 to produce the complete signal wave as represented in Fig. 20. This complete wave appears in the output connection 92 from the tube 102, and is supplied to a transmitter 15 168.

From the foregoing it will be understood that the signals represented at 144, 148 and 152, and which are applied to the grid circuit of the tube 96, make the undesirable signals represented at 146 and 150 sufficiently negative to permit these undesirable signals to be eliminated by the tubes 98 and 102, as explained. The signals as represented at 144 and 148, also, are effective to cut off the ray during the periods of return deflection thereof in both the horizontal and vertical directions. In the complete wave as represented in Fig. 20, the signals represented at 144 and 148 30 serve as pedestals upon which the synchronizing and framing signals appear, and the latter are of the same polarity as and substantially greater in amplitude than the peak black picture signals. The receiving apparatus can therefore readily 35 distinguish the picture signals from the synchronizing and framing signals by amplitude selection. It is to be noted that the synchronizing signals are of very short duration as compared with the duration of the signals as represented at 144, the period of duration of the synchronizing signals being only sufficient to drive the horizontal deflection circuit 30. Also, it is to be noted that the framing signals are of very short duration as compared with the duration of the signals represented at 152. The duration of the framing signals is only sufficient to effectively 40 drive the vertical deflection circuit 34.

An important feature of my improved system and method of operation resides in the fact that 50 the synchronizing and framing signals are combined with the picture-signal wave only after the undesirable signals, such as those represented at 146 and 150, have been removed. In the specific embodiment of my invention disclosed, this 55 is accomplished by supplying the synchronizing and framing signals to the amplifier at a point beyond the two tubes 98 and 102.

The receiving apparatus shown diagrammatically in Fig. 21 comprises a radio receiver and 60 amplifier 170. A resistance 172 is connected across the output circuit of the receiver 170, and by a connection 174 from this resistance the wave of Fig. 20 is applied to the control grid 176 of an electron gun 178, similar in construction 65 and manner of operation to the gun 18 of the transmitter tube. The gun 178 is disposed at one end of the tube 180 and operates to develop and direct a ray 182 of electrons at a fluorescent screen 183 on the large end of the tube. Electromagnetic coils 184 and an associated horizontal deflection circuit 185, similar to the circuit 30, operate to deflect the ray 182 horizontally 70 at the rate of 7290 times a second.

Electromagnetic coils 186 and an associated 75

circuit 188, similar to the vertical deflection circuit 34, operate to deflect the ray vertically at the rate of 60 times a second. The ray 182 is therefore made to scan the screen 183 in the same manner and along the same pattern as the ray 20 scans the screen 12 of the transmitter tube.

The incoming wave, as represented in Fig. 20, is applied to the input circuit of a rectifier tube 190 which is biased to pass only the synchronizing and framing signals which are of substantially greater amplitude than the peak "black" picture signals.

The synchronizing and framing signals are separated by a filter connected in the output circuit of the tube 190. This filter comprises a condenser 192 across which substantially only the framing signals appear, and these are supplied to the vertical deflection circuit 188 by a connection 194. The filter also comprises a resistor 196 across which substantially only the synchronizing signals appear, and these are supplied by a connection 198 to the horizontal deflection circuit 185. The ray 182 is caused to scan the screen 183 sixty times a second, the spaced horizontal lines of the thirty even frames falling in the spaces between the spaced horizontal lines of the thirty odd frames. During the return deflection of the ray 182 in the horizontal direction it is cut off by the signals represented at 144 in Fig. 13, and during return deflection of the ray in the vertical direction it is cut off by the signals represented at 152 in Fig. 14.

35 The intensity of the ray 182 is varied by the picture signals to produce the image on the screen 183.

The construction of the filter 65 in the transmitting apparatus is the same as the filter shown 40 in the receiving apparatus.

The details of construction of the receiving apparatus may be made in accordance with the disclosure in the copending application by Arthur W. Vance, Serial No. 544,959, filed June 17, 45 1931.

The details of construction of the horizontal and vertical deflection circuits 30, 34, 185 and 188 may be made in accordance with the disclosure in the copending application by Tolson et al., 50 Serial No. 595,484, filed February 27, 1932.

For the purpose of transmitting the direct current component referred to, I propose to employ a photoelectric cell 200 and support the same, as shown in Fig. 1, adjacent the outer edge of 55 the disc 40, between the disc and the film gate 48. In operation, as the pictures of the film pass through the gate 48, the light is reflected from the surface of the disc 40 to the cell 200, whereupon a current is developed whose amplitude 60 varies proportionally with occurring variations in the average brilliancy or background of the pictures. This current is amplified in a D. C. amplifier 202, shown in detail in Fig. 22. As the current from the cell 200 flows through the battery 203 and the potentiometer 204 in Fig. 22, the grid of the tube 206 is made more or less negative, depending upon the value of the current. This causes the plate current of this tube 70 to decrease correspondingly through the rheostat 208 to cause the potential at the point 210 to become more or less positive. This positive voltage is filtered by a condenser 212 and is connected as shown in Fig. 1 to the grid leak 214 of 75 the tube 102, through a potentiometer 216 and a

battery 218 which may be used as an auxiliary manual control when desired.

In operation, the bias of the tube 102 is varied in accordance with variations in the average brilliancy or so-called background brilliancy of the 5 pictures being transmitted, and this action controls the height or effective amplitude of the transmitted synchronizing signals by varying the voltage input to this tube at which cut off occurs. In other words, the amplitude of the synchronizing signals, measured from the A. C. axis of the entire wave as represented in Fig. 20, varies proportionately with the background brilliancy of the object. With proper provisions made at the receiving station, the intensity of the ray is 15 varied so that the background or average brilliancy of the reproduced picture varies with occurring variation of the background at the object. Since the details of construction of the receiving apparatus for this purpose are not part of my 20 present invention, no disclosure thereof has been made. However, a television receiving apparatus capable of operating in this manner and for the purpose referred to is disclosed in detail in the copending application by Ralph S. Holmes, 25 Serial No. 658,894, filed February 28, 1933. As a variation, the tube 206 in Fig. 22 may be of the well known variable-mu type which has a very non-linear characteristic, and its bias and working level adjusted to correct for the non-linearity 30 of the light vs. grid voltage characteristic of the receiver tube 180.

As a modification, the cell 200 may be supported to the left of the lens 220 in Fig. 1 to receive the light reflected therefrom instead of 35 the light reflected from the disc 40. Also, the cell 200 may be supported adjacent the tube 10 to receive the light from the screen 12 when the object is an outdoor or studio scene.

It is important to note that in my improved 40 system and method of operation the control wave, which provides for the so-called direct current component at the receiver, is applied to the grid circuit of the tube 102. That is, this wave is applied to the signal amplifier only after practically all of the undesirable signals referred to have been eliminated by the tube 98, as explained.

As a modification, the various sets of openings or slits in the single disc 54 may be made in as 50 many different discs, all fixed on the shaft of the motor 56 and angularly related to produce the signals in the same way as the single disc. It will be understood that in such case the photoelectric cells and the light sources will be associated with their respective discs.

From the foregoing it will be seen that I have provided an improved television system and method of operation thereof whereby it is possible to obtain the advantages of the so-called interlaced scanning action, and to maintain this action although there might occur some degree of misadjustment which would otherwise interfere with the desired operation. As explained, I accomplish this by my improved system and method whereby the framing signals for the odd and 65 even frames are for all practical purposes identical in size and shape, after passing through the separating filters.

Further, it will be seen from the foregoing that my improved system and method of operation 70 makes provision for the supply of synchronizing signals continuously to the circuit for deflecting the cathode rays horizontally. In this connection, I believe myself to be the first, for this same purpose, to interrupt the framing signals and to 75

cause synchronizing signals to appear during the periods of interruption of the framing signals.

Further, it will be seen that by improved system and method of operation provision is made for the transmission of a control wave which can be utilized at the receiver to control automatically the background of the reproduced picture.

Further, it will be seen that by my improved system and method of operation the undesirable signals referred to are eliminated in at least two steps at the transmitter by employing signals to cut off certain tubes during the periods of occurrence of the undesirable signals.

While but one embodiment of my invention has been disclosed, it is understood that various modifications, within the conception of those skilled in the art, are possible without departing from the spirit of my invention or the scope of the claims.

I claim as my invention:

1. In the art of television, the method of operation which comprises developing synchronizing signals at a relatively high line-scanning frequency and framing signals at a relatively low framing frequency, amplifying said signals, and causing the synchronizing signals to occur at a frequency substantially greater than the line-scanning frequency only during substantially the periods of occurrence of the framing signals.

2. In a system for communication by television, a scanning device for developing picture signals, means for causing scanning action of said device at a given uniform rate, a multi-tube electrical circuit supplied with picture signals from said device, means supplying a tube of said amplifier with signals occurring at said rate and each of the same polarity as and greater in amplitude than any of the picture signals representative of conditions of shade at the object, and means supplying to a tube between said first-named tube and the output tube of said circuit control signals occurring at said rate and being of the same polarity as and in phase with said second-named signals.

3. In a system for communication by television, a scanning device for developing picture signals, means for causing scanning action of said device at a given uniform rate, a multi-tube electrical circuit supplied with picture signals from said device, means for supplying to said circuit a first set of control signals occurring at said rate, at least one of the tubes of said circuit being cut off by each of the control signals, and means for supplying to said circuit a second set of control signals of the same polarity as and in phase with the first set of control signals, each of the signals of the second set being of shorter duration than those of the first set.

4. In a television system, a scanning device, means for causing scanning action of said device, means for developing and supplying to said first-named means control signals at a relatively high line frequency and other control signals at a relatively low framing frequency and with the individual framing signals interrupted and with signals at the relatively high frequency occurring during the periods of interruption of the framing signals, said second-named means comprising a light-sensitive device, a light source, a rotatable member for controlling the manner of illumination of said light-sensitive device by the light source and for interrupting the light at least once during the periods of occurrence of the individual framing signals, and means for

rotating said member in time with the frequency of occurrence of the framing signals.

5. In a television system, a cathode ray scanning device provided with a screen, means for developing a ray of electrons and directing the ray at said screen, means for deflecting the ray in one direction at a relatively high frequency and means for simultaneously deflecting the ray in a different direction at a relatively low frequency to cause the ray to scan said screen, means for generating and supplying synchronizing signals at the relatively high frequency to said second-named means and framing signals at the relatively low frequency to said third-named means, with the individual framing signals interrupted and with some of the synchronizing signals occurring during the periods of interruption of the framing signals, and an amplifier for amplifying the synchronizing and framing and picture signals.

6. In a television transmitting system, a scanning device for developing picture signals, a multi-tube amplifier for amplifying the picture signals, means for generating electrical signals at a given frequency and applying the same to a tube of said amplifier under conditions whereat these signals are of the same polarity as the picture signals representative of conditions of shade at the object being transmitted, the amplitude of said electrical signals being sufficient to bias said tube to cut off, and means for generating control signals at said given frequency and applying the same to a tube of said amplifier under conditions whereat these signals are of the same polarity as said electrical signals.

7. In a television transmitting system, a scanning device for developing picture signals, a multi-tube amplifier for amplifying the picture signals, means for generating electrical signals at a given frequency and applying the same to a tube of said amplifier under conditions whereat these signals are of the same polarity as the picture signals representative of conditions of shade at the object being transmitted, the bias on said tube being at a value to permit passage through the same of substantially all of the picture signals at said polarity, the amplitude of said electrical signals being sufficient to bias said tube to cut off, a second tube supplied from said first tube with said electrical signals at said polarity and biased to pass substantially all of the picture signals at said polarity and to be cut off by said electrical signals, and means for generating control signals at said given frequency and applying the same to a circuit in said system on the output side of said second tube and under conditions whereat these signals are of the same polarity as said electrical signals.

8. In the art of television transmission, the method of operation which comprises generating a picture-signal wave, generating and adding to said wave electrical signals occurring at a given frequency and which are of the same polarity as the picture signals representative of conditions of shade at the object and at least of the same amplitude as the peak picture signals of said polarity, and generating and adding to said wave control signals at said polarity and which occur in phase with said electrical signals.

9. In the art of television transmission, the method of operation which comprises generating a picture-signal wave, generating and adding to said wave electrical signals occurring at a given frequency and which are of the same polarity as the picture signals representative of conditions

- of shade at the object and at least of the same amplitude as the peak picture signals of said polarity, and generating and adding to said wave control signals at said polarity and which occur in phase with said electrical signals and which are of shorter duration than the latter.
10. In the art of television transmission, the method of operation which comprises generating a picture-signal wave, generating and adding to said wave electrical signals of the same polarity as the picture signals representative of conditions of shade at the object and at least of the same amplitude as the peak picture signals of said polarity, some of said signals occurring at a relatively high synchronizing frequency and others occurring at a relatively low framing frequency, generating and adding to said wave control signals at said polarity and which occur in phase with the electrical signals at said relatively high frequency, and generating and adding to said wave other control signals at said polarity and which occur in phase with the electrical signals at said relatively low frequency.
11. In a television transmitting system, a scanning device for developing picture signals, means for causing scanning action of said device at a given frequency, means for generating control signals at said frequency, a multi-tube amplifier for the picture signals, means for generating blanking signals and for applying them to one of the tubes of said amplifier, means for developing a signal wave which varies in accordance with occurring variations in overall brilliancy of the object being transmitted, a connection for applying the signal wave to the grid circuit of a tube of said amplifier which is subsequent to said one tube, and a connection for applying the control signals to said amplifier on the output side of said last-mentioned tube.
12. In a television transmitting system, a scanning device for developing picture signals, means for causing scanning action of said device at a given frequency, means for generating control signals at said frequency, a multi-tube amplifier for the picture signals, means for generating blanking signals and for applying them to one of the tubes of said amplifier, means for developing a direct current which varies in accordance with occurring variations in overall brilliancy of the object being transmitted, a connection for applying the direct current to the grid circuit of a tube of said amplifier which is subsequent to said one tube, and a connection for applying the control signals to the amplifier on the output side of said last-mentioned tube.
13. In a television transmitting system, means for generating horizontal scanning synchronizing impulses, means for generating vertical scanning synchronizing impulses each of longer time-duration than a horizontal synchronizing impulse, means for interrupting the continuity of each vertical synchronizing impulse, amplifying means for said impulses, and means for introducing into the system a horizontal synchronizing impulse during each interruption period whereby, at a receiver, the periodicity of the horizontal synchronizing impulses is not impaired.
14. In a television transmitting system, means for generating horizontal scanning impulses, means for generating vertical scanning synchronizing impulses at a frequency incommensurable with the frequency of the horizontal impulses and means for periodically increasing the integrated energy-content of the horizontal impulses at time periods immediately before the occur-

rence of the vertical impulses whereby, after integration in a receiving device, the energy content of each vertical impulse is substantially the same as that of every other vertical impulse.

15. Control apparatus comprising means for developing control signals at a relatively high frequency, means for developing control signals at a relatively low frequency and with the individual signals at the relatively low frequency interrupted, and means for supplying an electrical circuit with said high frequency signals and said low frequency signals at the same polarity with respect to each other and with some of the signals at the relatively high frequency occurring respectively during the periods of interruption of the signals at the relatively low frequency.

16. Control apparatus comprising means for developing control signals at a relatively high frequency, means for developing control signals at a relatively low frequency and with the individual signals at the relatively low frequency interrupted for a period greater than the period of occurrence of the individual signals at the relatively high frequency, and means for supplying an electrical circuit with said high frequency signals and said low frequency signals at the same polarity with respect to each other and with some of the signals at the relatively high frequency occurring respectively during the periods of interruption of the signals at the relatively low frequency.

17. In a television system comprising a scanning device for obtaining scanning action at a relatively high rate of m lines per second and a relatively low rate of n frames per second, an electrical channel for amplifying synchronizing signals effective at the rate of m times per second and for amplifying framing signals effective at the rate of n times per second, means for developing and supplying the synchronizing signals to said amplifier channel, and means for developing and supplying the framing signals to said amplifier channel and in an interrupted fashion during each framing period with at least some of the interruption periods in phase with the periods of occurrence of the synchronizing signals.

18. In the art of television, the method of operation which comprises developing a synchronizing signal which recurs at a relatively high frequency, developing an interrupted framing signal which recurs at a relatively low frequency with the interruption periods in phase with and of greater duration than the periods of occurrence of the synchronizing signals, and amplifying said signals.

19. In the art of television, the method of operation which comprises developing synchronizing signals at a relatively high frequency of m per second, developing interrupted framing signals at a relatively low frequency of n per second with the interruption periods of the framing signals occurring in phase with and being of greater duration than the periods of occurrence of the synchronizing signals,

$$\frac{m}{n}$$

being equal to $x+y$, x being a whole number and y being less than one, and developing additional signals which are similar to the synchronizing signals and which occur only during substantially the periods of occurrence of the framing signals at the frequency of at least m per second

- and in such time relation to the synchronizing signals that the effect is produced of having synchronizing signals occur at the rate of at least 2m per second.
- 5 20. In a television system, a scanning device, means for causing scanning action of said device, means for developing synchronizing signals at a relatively high line frequency and framing signals at a relatively low framing frequency 10 with the individual framing signals interrupted and with the synchronizing signals occurring during the periods of interruption of the framing signals, and means for supplying said signals to said first named means.
- 15 21. In a television system including means for generating picture signals periodically, there being undesired signals generated at the end of each period of picture signal generation, the method of operation which comprises so changing the amplitude location of said undesired signals that they are removed from the region of said picture signals, clipping off said undesired signals whereby a pedestal is produced at the end of each of said periods, and adding a synchronizing impulse to the top of each of said pedestals.
- 20 22. In a television system including means for generating picture signals periodically, there being undesired signals generated at the end of each period of picture signal generation, means for so changing the amplitude location of said undesired signals that they are removed from the region of said picture signals, means for clipping off said undesired signals whereby a pedestal is produced at the end of each of said periods, and means for varying the height of said pedestals in accordance with the average illumination of the image being transmitted.
- 25 23. In a television system including means for generating picture signals periodically, there being undesired signals generated at the end of each period of picture signal generation, means for so changing that amplitude location of said undesired signals that they are removed from the region of said picture signals, means for clipping off said undesired signals whereby a pedestal is produced at the end of each of said periods, means for varying the height of said pedestals in accordance with the average illumination of the image being transmitted, and means for generating synchronizing impulses and for adding one of said synchronizing impulses to the top of each of said pedestals.
- 30 24. In a television system including means for generating picture signals periodically, there being undesired signals generated at the end of each period of picture signal generation, means for so changing the amplitude location of said undesired signals that they are removed from the region of said picture signals, means for clipping off said undesired signals whereby a pedestal is produced at the end of each of said periods, means for varying the height of said pedestals in accordance with the average illumination of the image being transmitted, and means for generating synchronizing impulses which are narrow as compared with the width of said pedestals and for adding one of said synchronizing impulses to the top of each of said pedestals.
- 35 25. In a television system including means for generating picture signals periodically, there being undesired signals generated at the end of each period of picture signal generation, means for so changing the amplitude location of said undesired signals that they are removed from the region of said picture signals, means for clipping off said undesired signals whereby a pedestal is produced at the end of each of said periods, and means for increasing the height of said pedestals in response to an increase in the average illumination of the image being transmitted.
- 40 26. In a television system including means for generating picture signals periodically, there being undesired signals generated at the end of each period of picture signal generation, means for producing blanking impulses which occur at the same time as said undesired signals, means for adding said blanking impulses and said picture and undesired signals whereby said undesired signals are removed from the region of said picture signals, means for clipping off said undesired signals whereby a pedestal is produced at the end of each of said periods, means for producing synchronizing impulses which occur at the same time as said pedestals, and means for adding said synchronizing impulses to said pedestals.
- 45 27. In a television system for the production of pictures at a certain frame frequency and at a certain scanning line frequency, means for producing interrupted rectangular impulses occurring at said frame frequency, means for producing rectangular impulses occurring at a frequency which is a multiple of said scanning line frequency and which have a width which is less than the width of said interruptions, and means for so combining said interrupted impulses and said multiple frequency impulses that said multiple frequency impulses are located in said interruptions.
- 50 28. In the art of television, the method of operation which comprises developing a synchronizing signal which recurs at a relatively high frequency of m per second, developing an interrupted framing signal which recurs at a relatively low frequency of n per second with the interruption periods of the framing signals occurring in phase with and being of greater duration than the periods of occurrence of the synchronizing signals,
- $\frac{m}{n}$
- being equal to a whole number plus
- $\frac{1}{k}$
- k being a whole number less than 8, and developing additional signals which are similar to the synchronizing signals and which occur only during substantially the periods of occurrence of the framing signals at the frequency of at least m per second and in such time relation to the synchronizing signals that the effect is produced of having synchronizing signals occur at the rate of at least 2m per second.
- 55 29. In a television transmitting system, means for generating horizontal synchronizing impulses occurring at a relatively high frequency of m per second, means for generating vertical synchronizing impulses at a relatively low frequency of n per second,
- $\frac{m}{n}$
- being equal to a whole number plus
- $\frac{1}{k}$
- k being a whole number less than 8, and means for periodically increasing the integrated energy

content of the horizontal synchronizing impulses at time periods immediately before the occurrence of the vertical synchronizing impulses whereby, after integration in a receiving device, the energy content of each vertical impulse is substantially the same as every other vertical impulse.

30. In a television system including means for generating picture signals periodically, means for producing a rectangular voltage impulse at the 10 end of each period of picture signal generation, means for producing synchronizing voltage impulses which occur at the same time as and which are narrower than said rectangular impulses, and means for so adding said picture signals, said 15 rectangular impulses and said synchronizing impulses that a synchronizing impulse is located on the top of each rectangular impulse.

31. In a television system including means for generating picture signals periodically, there being 20 undesired signals generated at the end of each period of signal generation, means for so changing the amplitude location of said undesired signals that they are removed from the region of said picture signals, means for clipping off at 25 least a portion of said undesired signals whereby the position of the alternating current axis for the picture signals and the undesired signals is changed, and means for again clipping off at least a portion of said undesired signals.

32. In television apparatus, means for producing 30 horizontal synchronizing impulses which occur at a relatively high frequency, each of said impulses having a front or leading edge, and means for producing framing impulses which occur at a relatively low frequency and which have 35 slots therein that have a back or trailing edge which occurs in the same time relation as said leading edges whereby the time intervals between the successive above-mentioned edges are the 40 same.

33. In television apparatus, means for generating 45 horizontal synchronizing impulses which occur at a relatively high frequency, each of said impulses having an edge which changes abruptly in a certain direction with time, and means for generating framing impulses which occur at a relatively low frequency and which have slots 50 therein that have an edge which changes abruptly in said certain direction and which occurs in the same time relation as the said edges of said horizontal synchronizing impulses whereby the 55 time intervals between the successive above-mentioned edges are the same.

34. The invention according to claim 33 characterized 55 in that additional means is provided for generating during the periods immediately preceding each framing impulse impulses which occur at a rate which is a multiple of the frequency at which the horizontal synchronizing impulses 60 occur.

35. In a television system, means for scanning 65 a view to be transmitted and developing picture signals, means for transmitting a horizontal synchronizing impulse at the end of each scanning line, said impulse having an edge which changes abruptly in amplitude in a certain direction with respect to time, means for transmitting framing impulses at the end of each picture frame which impulses have slots therein having an edge which 70 changes abruptly in amplitude in said certain direction with respect to time and which occurs in the same time relation as the said edges of said horizontal synchronizing impulses whereby the time intervals between the successive above-mentioned edges are the same.

36. The invention according to claim 35 characterized in that there is additional means for producing auxiliary impulses which occur during the periods immediately preceding and immediately following each framing impulse and which in combination with the horizontal synchronizing impulses form a group of regularly recurring impulses.

37. In a television system, means for generating 10 horizontal synchronizing impulses which occur at a relatively high frequency, means for generating slotted framing impulses which occur at a relatively low frequency, and means for generating a group of impulses immediately preceding each framing impulse which impulses occur at a 15 rate which is a multiple of the frequency at which said horizontal synchronizing impulses occur, said slots occurring at said multiple frequency and the trailing edges of said slots occurring in the same time relation as the leading edges of 20 said impulses in said group of impulses.

38. The invention according to claim 37 characterized in that said last means includes means for making at least one of the impulses in said group of a different width or duration than the 25 other impulses in said group.

39. The invention according to claim 37 characterized in that said last means includes means for generating a group of impulses immediately following each framing impulse which impulses 30 occur at a rate which is a multiple of the frequency at which said horizontal synchronizing impulses occur, said last mentioned impulses having leading edges which occur in the same time relation as the trailing edges of said slots. 35

40. In a television system, means for generating 40 horizontal synchronizing impulses which occur at a relatively high frequency, and means for generating groups of framing impulses which groups occur at the relatively low framing frequency, each of the impulses in one of said groups following one of said horizontal synchronizing impulses.

41. In a television system, means for generating 45 horizontal synchronizing impulses which occur at a relatively high frequency, each of said impulses having a front or leading edge, and means for generating framing impulses which occur at a relatively low frequency and which have evenly spaced slots therein that have a back or trailing 50 edge, the back or trailing edge of each alternate slot occurring in the same time relation as the said leading edges whereby the time intervals between the successive leading edges of the horizontal synchronizing pulses and the successive 55 trailing edges of said alternate slots are the same.

42. In a television system, means for generating 60 horizontal synchronizing impulses which occur at a relatively high frequency, and means for generating framing impulses which occur at a relatively low frequency and which have slots 65 therein occurring in a fixed phase or time relation to said high frequency impulses.

43. In the art of television, the method of operation which comprises developing a synchronizing signal which recurs at a relatively high frequency, developing an interrupted framing signal which recurs at a relative low frequency with the interruption periods in a fixed phase relation to the periods of occurrence of the synchronizing signals.

44. A method of providing synchronizing signals for use at a television receiver employing interlaced scanning, said method comprising generating line synchronizing pulses, generating 76

groups of pulses, each of which groups constitutes a frame signal, causing said groups of pulses to provide, during at least the earlier part of each of said frame signals, leading edges 5 which occur at n times the frequency of said line pulses where n is a small integer representing the number of traversals in which the object to be transmitted is completely scanned, causing certain of said leading edges to occur in phase 10 with the leading edges of said line pulses, so that leading edges occur at line frequency throughout said synchronizing signals, and transmitting said line pulses and frame signals.

45. A method according to claim 44, in which 15 said line pulses and the pulses constituting said frame signals are generated with a substantially rectangular wave form.

46. A method of providing synchronizing signals for use at a television receiver employing 20 interlaced scanning, said method comprising generating line synchronizing pulses in the intervals between trains of picture signals representative 25 of lines of the object to be transmitted, generating auxiliary line pulses occurring at n times the frequency of said line pulses where n is a small integer representing the number of traversals in which said object is completely scanned, causing every n th leading edge of said auxiliary line pulses to occur in phase with the leading 30 edges of said line pulses, transmitting said line

pulses during traversals of said object and transmitting said auxiliary line pulses between successive traversals of said object.

47. A method according to claim 46, in which said line pulses and said auxiliary line pulses 5 are generated with a substantially rectangular wave form.

48. A method according to claim 46, in which said line pulses and said auxiliary line pulses are generated with substantially the same 10 amplitude.

49. A method of providing synchronizing signals for use at a television receiver employing interlaced scanning, said method comprising generating line synchronizing pulses in the intervals 15 between trains of picture signals representative of lines of the object to be transmitted, generating frame synchronizing signals having a duration greater than the interval between successive line pulses, suppressing parts of said frame 20 signals for forming in at least the early part of each frame signal leading edges which occur at n times the frequency of said line pulses where n is a small integer representing the number of traversals in which said object is completely 25 scanned, causing certain of said leading edges to occur in phase with leading edges of said line pulses, and transmitting said line pulses and frame signals.

ALDA V. BEDFORD. 30
